SPLINT

Filed Jan. 24, 1930

UNITED STATES PATENT OFFICE

CHARLES F. CLAYTON, OF FORT WORTH, TEXAS

SPLINT

Application filed January 24, 1930. Serial No. 423,090.

My invention relates to splints for fracture of the clavicle; and the object is to provide splints for holding fragments of broken parts in their normal positions and preventing overriding of fragments on each other for the purpose of making possible recovery without deformity, and to provide devices which will be comfortable to the body and which will not irritate parts of the body. Other objects and advantages will be fully explained in the following description and the invention will be more particularly pointed out in the claims.

Reference is had to the accompanying drawings which form a part of this application.

Fig. 1 is a perspective view of the splint assembled.

Fig. 2 is a plan view of the upper bar or supporting brace, showing its connections.

Fig. 3 is a perspective view of the front parts of the splint.

Fig. 4 is a perspective view of the rear connections for the splints.

Similar characters of reference are used to indicate the same parts throughout the several views.

The splint is provided with a front supporting brace in two parts 1 and 1. These parts are slidably connected by their ends which are slotted and connected to each other by bolts 15 and nuts 16. The brace is thus adjustable for different sizes of patients. The splint has on its outer ends kidney-shaped pads 2 which are connected to ends of the splint by ball and socket joints or swivel connections. The pads 2 are located substantially between the tips of the shoulder and the clavicle so that the splint will not irritate the parts of the body. The bars 1 are curved towards their ends to form concave surfaces and straight bars 4 are riveted or welded or otherwise attached to the bar 1, leaving elongated spaces between the bars 4 and the bar 1 for vertical bars 5. The object of the spaces 17 is to provide for adjustment of the bars 5 laterally. The vertical bars 5 have elongated slots at their juncture with the bars 4 so that the bars 5 may be adjusted vertically for adjustment to bodies

of different lengths or shape. Towards their upper ends the bars 5 are curved to conform to the body and must be extended sufficiently above the shoulders so that they will not rest on the shoulders. The bars 5 are secured to bars 4 by clamps 6. The bars 5 at their upper and rear extremity are provided with buckles 7 and means for attaching the buckles 7 to the bars 5.

The bars 5 have bayonet forward projections intermediate their connection with the bars 4 and their lowest points and at their lower extremities these bars 5 are bent at right angles and extended backwardly. Pads 14 are connected to the bars 5 at their lowest points by ball and socket joints or swivel connections to prevent the metal from injuring the body and to make the splint easily engage the body and to distribute the pressure on the body at the points where the metal of the bars would not be yielding.

A buckle 13 is connected to one end of the bar 5 and a strap 12 is caught by the buckle 13. The other end of the strap 12 is detachably connected to the other end of the bar 5, the strap 12 being easily flexible and extended behind the body, for attaching the splint to the body. The straps 11 and 10 are caught in the buckles 7 which are attached to the rear upper extremities of the bar 5. The straps 10 and 11 are crossed and extended down to the lower horizontal members of the bars 5 and connected thereto by ball and socket joints or swivel connections.

What I claim is:

1. A clavicle splint comprising a longitudinal bar in two parts adjustably connected together, said bars being curved backwardly at their outer ends and curved pads attached thereto, straight bars spanning the curved portions of said bar and attached thereto, vertical braces projected through the spaces between said straight bars and the curved portions of the horizontal bar and curved above the shoulders and extended below said bars, angular extensions of said braces extending backwardly, pads pivotally connected to said braces at their lowest extremities, straps attached to the upper extremities of said braces and crossed and attached to

the rear terminals of said angular extensions, and one strap attached to the terminals of said angular extensions and extended horizontally behind the back of the wearer.

- 5 2. A clavicle splint comprising a bar in two parts adjustably connected together and curved backwardly at their terminals and curved pads pivotally connected thereto for holding the shoulders and clavicle bones in their normal positions, straight bars spanning the curved portions of said horizontal bar and attached thereto to form spaces for lateral adjustments, vertical braces extended through said spaces and adjustable on said 10 straight bar and extended above the shoulders of the patient with curved terminals and extended downwardly from said first named bar with forward offsets above their lowest extremities, said bars having right angular 15 extensions backwardly from their lowest extremities, pads pivotally connected to said vertical braces at their lowest extremities, and flexible straps for securing said vertical braces to the body.
- 20 3. A clavicle splint comprising an expandible and contractible holding bar extending across and in front of the body and provided with curved terminals, curved pads attached to said terminals for holding the shoulders and clavicle in normal position, straight bars 25 spanning said curved terminals and attached thereto and forming spaces for lateral adjustments of other braces, vertical braces fixedly adjustable on said straight bars and serving to hold said pads against the body, said vertical braces having their upper and lower terminals extended behind the body, flexible straps for engaging said terminals for binding the splint on the body, and pads 30 pivotally connected to said vertical braces at their lowest extremities to prevent the metal of the braces from injuring the body.
- 35 40

In testimony whereof, I set my hand, this 11th day of January, 1930.

CHARLES F. CLAYTON.
